(57) **CLAIM**

I claim the ornamental design for an infrared oil heater, thereof, as shown and described.

DESCRIPTION

FIG. 1 is a front perspective view for a “infrared oil heater” showing my new design,
FIG. 2 is a front view thereof,
FIG. 3 is a rear view thereof,
FIG. 4 is a left-side view thereof,
FIG. 5 is a right-side view thereof,
FIG. 6 is a top view thereof; and,
FIG. 7 is a bottom view thereof.
